AIR PRESSURE PUMPING MECHANISM

Walter B. Havens, Osawatomie, Kans., assignor of
one-half to Edwin V. Bedford, Osawatomie,
Kans.

Application November 10, 1939, Serial No. 303,832

5 Claims. (Cl. 103—248)

My invention relates to improvements in air pressure pumping mechanisms. It relates particularly to the type of pumping mechanisms in which a cylinder having a liquid inlet and a liquid outlet is located in a well containing a liquid, as water or oil, and in which compressed air is employed to force the liquid, that enters the cylinder by gravity, out of the cylinder to a desired place of delivery.

One of the objects of my invention is the provision of a novel arrangement of valves, which are actuated by a float in the cylinder, by which air under pressure is admitted to the cylinder at the time the exhaust of air therefrom is cut off, and by which the intake of compressed air is cut off when the air is being exhausted.

A further object of my invention is the provision of novel means by which one valve which controls the exhaust of air from the cylinder opens and closes another valve which controls the intake to the cylinder of compressed air simultaneously with the closing and opening of the exhaust valve.

A further object is the provision of novel means for releasably holding the exhaust valve in its closed position until it is forced to the open position by a valve operating mechanism.

Another object of my invention is the provision of a pumping mechanism of novel structure which is simple, strong, durable, compact and with relatively few parts, which is not likely to get out of order, and which is efficient in its operation.

The novel features of my invention are hereinafter fully described and claimed.

In the accompanying drawings, which illustrate the preferred embodiment of the invention,

Fig. 1 is a vertical sectional view of my improved pumping mechanism, showing the float in its most elevated position, the air exhaust valve closed, and the compressed air intake valve open.

Fig. 2 is a view of the pumping mechanism, partly broken away, partly in vertical section and partly in side elevation, showing the float in its lowermost position, the air exhaust valve open and the air intake valve closed.

Fig. 3 is a view similar to Fig. 2, with more parts broken away, showing the float in a raised position lower than that shown in Fig. 1, the air exhaust valve open and the air intake valve closed.

Fig. 4 is a section on the line 4—4 of Fig. 1.
Fig. 5 is a section on the line 5—5 of Fig. 1.

Fig. 6 is a section on the line 6—6 of Fig. 1.
Fig. 7 is a section on the line 7—7 of Fig. 1.
Fig. 8 is a section on the line 8—8 of Fig. 1.
Fig. 9 is a top view of what is shown in Fig. 1.
Fig. 10 is an enlarged horizontal fragmental 5
sectional view of a portion of the air exhaust
valve, shown in its closed position, and a portion
of the exhaust valve casing, the means for re-
leasably holding said exhaust valve being shown
in plan holding the exhaust valve closed. 10

Similar characters of reference designate simi-
lar parts in the different views.

The pumping mechanism is provided with a
pumping cylinder comprising a vertical pipe 1
internally threaded at its upper and lower ends. 15

Fitted in and closing the lower end of the
pipe 1 is a closure comprising a screw plug 2
having a central liquid inlet 3 in the upper end
of which is fitted a downwardly closing ball
valve 4. The plug 2 has on its inner side a cir-
cular tubular projection 5 encircling the inlet 3
and externally threaded. An internally threaded
guard cap 6 is fitted on the threaded periphery
of the tubular projection 5 and has lateral pas-
sages 7 for liquid above the projection 5. The
top of the cap 6 is spaced from the valve 4 a
distance such as to permit the valve 4 to open
without getting out of the tubular projection 5. 25

The externally threaded body 8 of a head is
fitted in the threaded upper end of the pipe 1
and closing said upper end. The space between
the head 8 and screw plug 2 forms a float cham-
ber 9 in the pipe 1. 30

For discharging the liquid which enters the
float chamber 9 through the inlet 3, there is
provided a vertical liquid discharge pipe 10 hav-
ing an externally threaded upper end fitted in a
central vertical threaded hole 11 in the head body
1. In the upper end of the hole 11 is fitted
the lower threaded end of another vertical dis-
charge pipe 12, which extends through a larger
central vertical hole 13 in the upper end of the
head body 8. Said larger hole 13 is adapted to
receive compressed air through an air conduct-
ing pipe 14, the lower end of which is threaded
and fitted in the threaded upper end of the hole
13. Said pipe 14 communicates with a source
of compressed air, not shown, but which may
be of any known suitable type. 35

The discharge pipe 10 extends in the float
chamber 9 to near the lower end thereof, and
has fitted on it a valve casing 15 having in its
lower end a liquid inlet 16 adapted to be closed
by a downwardly closing ball valve 17 disposed
in the valve casing 15 and adapted to rest on a 50
55

valve seat 18 in the upper end of the inlet 16.

The pumping cylinder is disposed in an oil well or a well containing water, and the liquid enters the float chamber 9 by gravity through the inlet 3. When the float chamber is filled to a predetermined height with the liquid, the latter is forced by compressed air, as will be hereinafter described, through the inlet 16, past the ball valve 17, into and through the pipe 10, hole 11, and pipe 12 to where the liquid is to be discharged.

For discharging exhaust air from the float chamber 9, as the liquid enters the chamber, the following described means is employed.

15 The lower end of the head body 8 is provided with a central vertical cylindrical hole 19 in the upper end of which is fitted a cylindrical inverted cup shaped member 20, against the lower end of which bears a circular plate 21 having a central hole 22. The member 20 and plate 21 form the casing of an air exhaust valve chamber 23. The top of the member 20 has two holes 24 which respectively communicate with two air exhaust ducts 25 that communicate with the outer air. The side wall of the member 20 is provided with two holes 26 respectively communicating with two inlet air ducts 27 which communicate with the float chamber 9, and extend through the side wall of the body 8, where the latter is spaced from the pipe 1, see Figs. 2 and 3.

The ducts 27, holes 26, valve chamber 23, holes 24 and ducts 25 form an air exhaust passage, which, when open, conveys exhaust air from the float chamber 9 to the outer air.

For holding the member 20 from revolving in the body 8, a pin 28 in the top of the member 20 is fitted in a hole in the body 8, see Fig. 1.

For closing the exhaust passage when compressed air is admitted into the float chamber 9, an air exhaust valve 29 is reciprocatively fitted in the exhaust chamber 23 to move from its open position, shown in Figs. 2 and 3, to a position in which it will close the lateral holes 26 in the member 20. Said exhaust valve 29 has a vertical tubular stem comprising an upper tube 30 which encircles the discharge pipe 10 and which extends downwardly into the float chamber 9 in which it has its threaded lower end fitted 50 on the upper internally threaded end of a lower tube 31, disposed vertically in the float chamber 9 and which encircles the discharge pipe 10, Fig. 1.

Rigidly fastened on the lower end of the lower 55 valve stem tube 31 is a collar 32 which forms an abutment against which is adapted to strike a float 33 which encircles the tube 31, and is adapted to be raised by the liquid in the float chamber 9 until it strikes an abutment 34, comprising a collar fastened by a set screw 35 on the upper tube 30 just above the upper end of the lower tube 31.

The liquid entering the float chamber 9 through the inlet 3 raises the float 33. When the upper 65 end of the float 33 engages the abutment collar 34 it will lift the valve stem 30-31 and the valve 29 until said valve strikes the upper end of the exhaust chamber 23 at which time the valve 29 will close the holes 26 and the ducts 27, thus shutting off the exhaust of air from the float chamber 9. To hold the valve 29 closed while compressed air is being discharged into the float chamber 9, to discharge the liquid therefrom, the following described yielding holding mechanism is provided.

Referring to Figs. 1 and 10, the exhaust valve 29 has extending inwardly from its periphery a radial hole 36 in which is mounted a coil spring 36', one end of which bears against the valve 29, and the other end of which bears against a ball 37, which, when the valve 29 is in the position shown in Fig. 1, the closed position, the ball will enter an annular groove 38 in the head body 8, and will yieldingly hold the exhaust valve 29 closed until the float 33 lowers and strikes the abutment 32 and forces the valve 29 downwardly to its open position, shown in Figs. 2 and 3.

For admitting compressed air into the float chamber 9, to expel the liquid therefrom, and for controlling such admission, the following mechanism is provided.

The body 8 under the plate 21 is fitted a cup shaped member 39, the upper edge of which bears against the plate 21, and which is supported by a circular collar 40, fastened by bolts 41 to the lower end of the body 8. The member 39 and the plate 21 forms an air intake valve chamber 42. The bottom of the cup shaped member 39 has a central hole 43 which registers with the hole in the collar 40, thus affording communication between the chamber 42 and the float chamber 9.

The wall of the member 39 has through it two holes 44 which respectively register with the lower ends of two air ducts 45 in the body 8, the upper ends of said ducts 45 communicating with the hole 13. The air supply pipe 14 discharges compressed air to the hole 13 in the upper end of the body 8. The said hole 13, the ducts 45, the holes 44, the air intake valve chamber 42, the hole 43 and the hole through the collar 40, form a passage for admitting compressed air to the float chamber.

Reciprocative in the air intake chamber 42 is an intake valve 46, which is movable from the raised open position, shown in Fig. 1, to the lower position, shown in Figs. 2 and 3, in which lower position it closes the air inlet holes 44, and thus shuts off the supply of compressed air to the float chamber 9.

The air intake valve 46 has a tubular stem 47 encircling the tubular stem member 30, and which extends through the hole 22 in the partition plate 21, into the valve chamber 23. The stem 47 also extends downwardly through the opening 43, and the plate 40 into the float chamber. In the float chamber 9 it has fastened to it a collar 48, by means of a set screw 49, which is adapted to be engaged by the abutment collar 34 and lifted, thus opening the valve 46, when the float 33 lifts the abutment collar 34, and closes the exhaust valve 29.

In operation, the parts being in the positions shown in Figs. 2 and 3, when liquid enters the float chamber 9 through the inlet 3, the liquid will raise the float 33 from the abutment collar 32. While the float is rising the exhaust valve 29 will remain open so that the air in the float chamber 9 above the liquid therein, will be exhausted through the ducts 27, holes 36, float chamber 23, and ducts 25 to the outer air.

When the float 33 contacts the upper abutment collar 34, the float will lift said collar and with it the exhaust valve 29 through its stem 30-31, closing the exhaust valve, thus shutting off discharge of air from the float chamber 9.

When the abutment collar 34 is thus lifted by the float 33, it will engage and lift the stem 47 and the intake valve 46, as shown in Fig. 1. The compressed air will then enter the float chamber 9.

through the pipe 14, hole 13, ducts 25, holes 44, intake valve chamber 42, holes 43 and hole in the collar 40.

The exhaust valve 29 will be held closed by the spring actuated ball 37 while the compressed air is forcing the liquid in the float chamber 9, through the valve casing 18, pipe 10, hole 11 and pipe 12.

As the liquid in the float chamber 9 is being discharged by the air pressure, the float 33 will lower and will contact with the abutment 32, forcing the latter downwardly, and thus moving the exhaust valve 29 downwardly to the open position, shown in Figs. 2 and 3. When the valve 46 was opened by the rising of the float, its stem 47 entered the exhaust valve chamber 23, as shown in Fig. 1. The exhaust valve 29 in moving downwardly to the open position, will engage the upper end of the valve stem 47 and will push the latter and the valve 46 to the closed position, shown in Figs. 2 and 3.

A complete cycle of operation has now been performed, and the exhaust valve 29 being open, and the air intake valve 46 closed, liquid will again begin to enter the float chamber 9, starting another cycle of operation, which will be performed in the manner hereinbefore described.

Many modifications of my invention, within the scope of the appended claims, may be made without departing from the spirit of my invention.

What I claim is:

1. In a compressed air pumping mechanism, the combination with a cylinder having a closed lower end, a valved liquid inlet, a head closing its upper end, and a float chamber between its ends, liquid discharge means communicating with said float chamber, said head having a passage for compressed air communicating with a supply source and discharging into said float chamber, said passage including an air intake valve chamber, said head having a passage for exhaust air communicating with the outer air and with said float chamber, said exhaust passage including an air exhaust valve chamber above said intake chamber, a piston exhaust valve vertically reciprocative in said exhaust chamber to and from an upper position in which it will close said air exhaust passage, and having a stem extending through said air intake chamber into said float chamber and in said float chamber having two spaced apart abutments one above the other, a piston valve vertically reciprocative in said air intake chamber to and from a lower position in which it will close said compressed air intake passage and having a tubular stem encircling said exhaust valve stem and extending into said exhaust chamber and adapted to be engaged and moved downward to the closed position by said exhaust valve and extending into said float chamber in the path of the upper of said abutments and adapted to be lifted thereby to the open position, and a float in said float chamber, between said abutments which are in the path of said float, the float in rising engaging and lifting said upper abutment until said exhaust valve is closed, and in lowering engaging said lower abutment and forcing it downwardly until said exhaust valve moves to its open position and closes said air intake valve.

2. In a compressed air pumping mechanism, the combination with a cylinder having a closed lower end, a valved liquid inlet, a head closing its upper end, and a float chamber between its ends, liquid discharge means communicating with said

float chamber, said head having a passage for compressed air communicating with a supply source and discharging into said float chamber, said passage including an air intake valve chamber, said head having a passage for exhaust air communicating with the outer air and with said float chamber, said exhaust passage including an air exhaust valve chamber above said intake chamber, a piston exhaust valve vertically reciprocative in said exhaust chamber to and from an upper position in which it will close said air exhaust passage, and having a stem extending through said air intake chamber into said float chamber and in said float chamber having two spaced apart abutments one above the other, a piston valve vertically reciprocative in said air intake chamber to and from a lower position in which it will close said compressed air intake passage and having a tubular stem encircling said exhaust valve stem and extending into said exhaust chamber and adapted to be engaged and moved downward to the closed position by said exhaust valve and extending into said float chamber in the path of the upper of said abutments and adapted to be lifted thereby to the open position, a float in said float chamber between said abutments which are in the path of said float, the float in rising engaging and lifting said upper abutment until said exhaust valve is closed, and in lowering engaging said lower abutment and forcing it downwardly until said exhaust valve moves to its open position and closes said air intake valve, and yielding means for holding said exhaust valve closed.

3. In a compressed air pumping mechanism, the combination with a cylinder having a closed lower end, a valved liquid inlet, a head closing its upper end, and a float chamber between its ends, said head having a passage for compressed air communicating with a source of supply and discharging into said float chamber, said passage including an air intake valve chamber, said head having a passage for exhaust air communicating with the outer air and with said float chamber, said exhaust passage including an air exhaust valve chamber above said air intake chamber, a liquid discharge pipe extending vertically through said valve chambers and into said float chamber and having in said float chamber a valved liquid inlet, a piston exhaust valve vertically reciprocative in said exhaust chamber to and from an upper position in which it will close said exhaust passage, and having a tubular stem encircling said discharge pipe and extending through said intake chamber into said float chamber and in said float chamber having two spaced apart abutments one above the other, a piston valve vertically reciprocative in said air intake valve chamber to and from a lower position in which it will close said air intake passage and having a tubular stem encircling said exhaust valve stem and extending into said exhaust chamber and adapted to be engaged and moved downward to the closed position by said exhaust valve and extending into said float chamber in the path of the upper of said abutments and adapted to be lifted thereby to the open position, and a float in said float chamber between said abutments which are in the path of said float, the float in rising engaging and lifting said upper abutment until said exhaust valve closes, and in lowering engaging and moving said lower abutment downwardly until said exhaust valve moves to its open position and closes said air intake valve.

4. In a compressed air pumping mechanism,

the combination with a closed cylinder having a float chamber, a valved liquid inlet and a head, liquid discharge means communicating with said float chamber, said head having a passage for compressed air discharging into said float chamber and including an air intake valve chamber, said head having a passage for discharging exhaust air communicating with the outer air and with said float chamber and including an exhaust air valve chamber, a piston valve reciprocative in said exhaust valve chamber to and from a position closing said exhaust passage and having a stem extending through said air intake chamber into said float chamber, a piston valve reciprocative in said air intake chamber to and from a position in which it will close said compressed air passage and having a tubular stem encircling said stem of said exhaust valve and extending into said exhaust chamber in the path of said

exhaust valve and movable by the latter to the closed position when said exhaust valve moves to the open position, a float in said float chamber, means actuated by said float for moving said exhaust valve to the closed position when said float rises to a predetermined point, means for moving said exhaust valve to the open position when said float lowers to a predetermined point, and means actuated by said exhaust valve when it moves to the closed position for moving said air intake valve to the open position. 5

5. In a compressed pumping mechanism, the combination set forth in claim 4 combined with means, independent of said float, for releasably holding said exhaust valve closed and operable to release said exhaust valve when said float lowers to a predetermined position. 10 15

WALTER B. HAVENS.
